SLEEVE PRESS

Ernest Davis, Syracuse, N. Y., assignor to The Prosperity Company, Inc., Syracuse, N. Y., a corporation of New York

Application October 12, 1944, Serial No. 558,373

6 Claims. (Cl. 223—57)

1

This invention relates to textile or laundry and garment pressing machines, and has for its object a machine for pressing sleeved articles, as the sleeves of garments, and particularly shirt sleeves, in which machine the forms on which the sleeves are placed are readily adjustable in a lengthwise direction to accommodate sleeves of different lengths. It further has for its object a particularly simple and efficient mounting and arrangement for the pressing elements which cooperate with the form or the sleeve thereon.

The invention further has for its object a padding on the form, which is shiftable lengthwise in order to break the padding away from the inner surface of the sleeve at the completion of the pressing operation.

The invention consists in the novel features and in the combinations and constructions hereinafter set forth and claimed.

In describing this invention, reference is had to the accompanying drawings, in which like characters designate corresponding parts in all the views.

Figure 1 is a front elevation of a preferable embodiment of this pressing machine.

Figure 2 is a side elevation, partly in section.

Figure 3 is a plan view looking downwardly in Figure 1.

Figures 4 and 5 are fragmentary side elevations illustrating the vertical adjustment of the form on which the sleeve is placed different elevations for pressing long sleeves.

Figure 6 is a fragmentary view, partly in section, of the form illustrating the sleeve or the padding thereof.

Figure 7 is a fragmentary view of the upper end of the form shown in Figure 6 showing the position of the padding when pulled upwardly relatively to the form against its returning springs.

Figure 8 is a plan view of one of the forms with clamps in place for holding the garment in place.

This pressing machine comprises, generally, a suitable frame, opposing upright pressing members mounted on the frame and having relative pressing movement, a spatulate or substantially flat padded form on which a sleeve is pressed shiftable into and out of between the opposing pressing faces, which are preferably flat, carrier means for the form including a table or platform shiftable to carry the form into and out of position between the pressing members, and also means by which the table or platform is shiftable vertically to carry the form to different elevations, and thereby make the machine adjusta-

ble for sleeves of different lengths. In pressing extra long sleeves, two pressing operations are performed, one for pressing part of the sleeve, and then the table is shifted upwardly to press the remainder of the sleeve, the pressing members being only of sufficient width or height to press shorter sleeves. As articles with sleeves, such as shirts, have two sleeves, the machine is formed double with two pairs of pressing members and two forms.

1 designates a frame; 2 a double intermediate upright pressing member having oppositely or outwardly presented pressing faces, which are substantially flat, and 3 are outside upright pressing members movable toward and from the pressing faces respectively of the intermediate pressing member 2. These pressing members 2, 3 are usually formed hollow and heated, as by steam, in any well known manner. The double 15 pressing member 2 is supported on the frame by supporting means including a column 4 having a bracket 5 on the upper portion thereof, carrying a forwardly and horizontally extending arm 6, which is provided with a casting or block 7 at its front end to which the opposing sides of the intermediate pressing members 2 are secured, the arm 6 extending between the pressing members 2. The outer movable pressing members 3 are also supported from the column 4 or 20 the bracket thereon, here shown as by yieldable arms or plates 8 anchored at like ends to the bracket 5 and secured at their opposite ends to the pressing members 3, the plates 8 being biased to separate the members 3 from the pressing faces of the double member 2 by springs 8a. The frame is enclosed in a suitable cabinet 9 formed with slots 10 aligned with the spaces between the pressing elements 2, 3. These slots also open 25 through the top of the cabinet.

30 11 designates the forms, these being usually flat metal plates tapered in accordance with the tapered article or sleeve from its lower end toward its upper end, the form having a thin padding 12 sleeved thereon, which has a shifting movement upwardly against the action of returning springs 13. The forms are provided with extensions 14 for maintaining a portion of the garment in upright position and with which clamps 14a coact to hold said garment in said 35 position. The clamps 14a maintain the cuff portions of the shirt in place during the ironing operation and are removed after the sleeves have been ironed.

35 The carrier mechanism for the forms comprises a platform or table 15 movable from a

position in front of the pressing elements rearwardly horizontally into a position to carry the forms between the pressing elements, a vertically movable base 16 movable along fixed guides 17 in the frame below the pressing elements and connections, as pairs of parallel links 18 between the base 16 and the table or platform 15 to carry the table or platform 15 substantially horizontally to shift the forms into and out of between the pressing members 2, 3. While the table 15 is being shifted from its forward position (Figure 2) to its rear dotted line position, the upper pivot 20 of each link 18 passes from the front side of a vertical plane intersecting its lower pivot 21 to the other side. A stop 15^a limits the rearward movement of the table when the form 11 is between the pressing members. The stop 15^a is shown as a roller which comes into engagement with and rides or rolls on the column 4. A second stop 19 limits the travel of the platform 15 to its forward position, it coming against the guide 17.

The table 15 is operated to carry the forms into and out of position between the pressing elements 2, 3 by hand, it being a simple matter for the operator to push or pull on the front edge T of the table 15. The pressing members 2, 3 are of sufficient height to press short sleeves or a portion only of a longer sleeve, so that to press the entire longer sleeve from the cuff to the shoulder seam, two pressing operations are necessary, and an adjustment of the table vertically is necessary to bring the unpressed portion of the long sleeve into a position between the pressing members. To effect such adjusting, the entire carrier mechanism is movable vertically as set forth, and this operation is effected by lifting the table up from a position, such as shown in Figure 4 to that shown in Figure 5, or pushing down from the position shown in Figure 5 to that shown in Figure 4. In order to facilitate the up and down shifting of the table, means is provided for counterbalancing the forms and the table or platform, and in the illustrated embodiment of the invention, a counterweight 22 is provided, this being shown as carried by a lever arm 23 pivoted at 24 to the frame and connected to the base 16 of the carrier mechanism as by a cable 25 pivoted at 26 to the lever 23 and running over an idler 27 mounted in the frame and connected at its other end at 28 to the base 16.

The movable pressing members 3 are operated preferably by air pressure applied to diaphragm chambers 29 carried by the frame, the diaphragms in said chambers operating through plungers or slides 30 against the outer sides of the pressing members 3 to compress them against the work on the forms in opposition to the tendency of the springs 8^a to open the members 3. The flow of air to and from the diaphragm is controlled by a suitable valve 31 operated by a pedal 32, the valve being connected in pipe lines connected to the pressure side of the diaphragm chambers 29. These valves are of a two-way, or combined intake and exhaust type, so that when the pedal is released, air exhausts from the diaphragm chamber, permitting the pressing members 3 to be opened by the re-action of springs 8^a.

In operation, the sleeves of a garment, as of a shirt, are placed on the two forms at the same time and pulled down until the sleeve fits the form, due to the taper of the sleeve and the form and are free of wrinkles. The upper ends of the forms are of such width as to prevent the cuffs from sliding down on the forms. The cuffs are clamped on the extensions 14 by the clamps 14^a. 75

The table 15 is then pushed rearwardly into between the pressing elements 2, 3 and the pressing elements 3 operated by operation of foot valve 31. After the initial pressing operation, if the sleeve is a relatively long one that can not be pressed in one operation, the table 15 is lifted to the desired height, as illustrated in Figure 5, to effect the pressing operation to the shoulder or including the arm seam and a portion of the body, the pressing elements 2, 3 are again operated. An operation may be considered as consisting of a closing and opening movement of the pressing elements 2, 3. The table 15 is then pulled forwardly, moving the forms out of position from between the pressing members. The operator then removes the clamps 14^a and taking hold of the garment or shirt sleeves pulls upwardly. The pad slides upward with the sleeve, if stuck thereto, and thus when the pads are no longer taut, they break away from the inner surface of the shirt, whereupon the shirt sleeves are removed readily from the forms and the padding.

What I claim is:

25 1. A press for sleeved articles including opposing upright pressing members having relative pressing movement and a spatulate form on which the articles are sleeved shiftable into and out of position between said members, means for effecting the relative pressing movement of the form and the pressing members, means for effecting shifting movement of the form into and out of position between the pressing members including supporting means for the form, and means for 30 adjusting the supporting means to carry the form to different elevations relative to the pressing members.

2. A press for sleeved articles including opposing upright pressing members having relative 40 pressing movement and a spatulate form on which the articles are sleeved shiftable into and out of position between said members, means for effecting the relative pressing movement of the form and the pressing members, means for effecting shifting movement of the form into and out of position between the pressing members including supporting means for the form, means for adjusting the supporting means to carry the form to different elevations relative to the pressing members, and means for counterbalancing the supporting means for the form.

3. A press for sleeved articles including opposing upright pressing members having relative 45 pressing movement and a spatulate form on which the articles are sleeved shiftable into and out of position between said members, means for effecting the relative pressing movement of the form and the pressing members, means for effecting shifting movement of the form into and out of position between the pressing members, including supporting means for the form, means for adjusting the supporting means to carry the form to different elevations relative to the pressing members, the form having an axially shiftable padding for breaking the padding away from the pressed sleeved article.

4. A press for sleeved articles including opposing upright pressing members having relative 50 pressing movement and a spatulate form on which the articles are sleeved shiftable into and out of position between said members, means for effecting the relative pressing movement of the form and the pressing members, means for effecting shifting movement of the form into and out of position between the pressing members, in-

cluding supporting means for the form, the form having a padding sleeved around the same and shiftable axially relative to the form for breaking the padding away from the pressed sleeved article.

5. A press for sleeved articles including a double intermediate pressing member having pressing faces on opposite sides thereof and outer pressing members coacting with the pressing faces respectively and having a pressing movement toward and from the same, means for effecting the pressing movement, an upright support common to the intermediate pressing member and to both outer pressing members, the support having an angular arm carrying the intermediate pressing member, and carrying means for the outer members also carried by said support, the support being located centrally of the pressing members in the rear thereof, said angular arm extending forward, and said carrying means being arms extending laterally and forward.

6. A press for sleeved articles including opposing upright pressing members having opposing pressing faces, a spatulate form on which the articles are sleeved shiftable into and out of position between said members, and carrier means for the form operable to position the form at different elevations relatively to the pressing members.

ERNEST DAVIS.
